GOTTFRIED NEUHAUS, OF EBERSWALDE, GERMANY.

SORTING MACHINE.

Application filed June 27, 1924, Serial No. 722,838, and in Germany June 27, 1923.

My invention relates to a machine for sorting corny or granular substances or materials, more especially corn or grain and the like, according to the weight, the shape, 5 and the quality of the respective substance or material; the chief object of my invention in the case of corn or grain is to obtain an unobjectionable seed-corn or seed-grain, and I attain the object in view by certain arrangements and combinations of parts, as 10 described hereafter.

I am aware of certain known sorting machines in which a casing or box enclosing the operating parts is supported on arch-shaped segments and the reciprocating or rocking motion is effected either by a connecting rod or by connecting rods, or by a link or by links engaging a reciprocating or rocking table at one of its ends. In contrast to that manner of supporting and rocking the casing or box together with the operating parts enclosed therein, all these parts are suspended in my improved machine from pendulums and are rocked by 20 two links or crank-guides attached to the long sides of a main-plate carrying the operating parts.

The sorting-table with its baffle-members is combined with a feeding device located 30 above it and serving also as a pre-sorting device in which the corny or granular substance or material is pre-sorted in such a manner that all parts of the table receive equal amounts of equal weight.

The table can be adjusted obliquely in various positions at right angles to the direction of the rocking motion. The degree of the obliquity depends upon the kind and quality of the substance or material to be 40 treated, and the means for adjusting the table obliquely and for securing it in its adjusted position consist, among other parts, chiefly of a rotatory eccentric combined with a nut-forming hand-wheel, as is all fully described hereinafter.

My invention is illustrated by way of example in the accompanying drawings, in which Figure 1 is chiefly a side-view of the machine, and partly (top of box or casing) a 50 vertical longitudinal section thereof; Figure 2 is partly a frontal view and partly a cross-

section in line C—D—E—F—G—H of Fig. 1; Fig. 3 shows some details drawn to an enlarged scale and in vertical section (plane J—K of Fig. 2); and Fig. 4 is a horizontal section through the feeding and pre-sorting device located in the top of the box or casing (section-plane: L—M of Figs. 1 and 2). Fig. 5 is a horizontal section through the sorting table (section-plane: Q—R of Fig. 60 1).

On the drawings (Figs. 1 and 2) 1 denotes four vertical standards secured to a foundation; they are connected with each other in pairs by strut-rods 1^a, and from each standard is suspended a pendulum-rod 2 by means of a bolt 3. The bolts are adjustable vertically in the tops of the standards by means of threaded spindles 4 and can be secured in their adjusted position by nuts 5.

Between the four standards 1 a horizontal plate 8 is arranged furnished with four oblique feet 6 connected with the free ends of the pendulums 2 by bolts 7. To the plate 8 are secured two cross-beams 9 9', and to each thereof is affixed a bearing 10 or 10' respectively, located in the middle of the respective cross-beam. The two bearings support a horizontal shaft 11 which carries the sorting table 12 on which baffle-members are provided 12^a (see Fig. 5) constituting channels 12^b on the surface of the sorting table 12 in known manner.

From the bottom of the plate 8 two crank-guides 13 and 13' located at the long sides of the plate and in the middle of each side extend downward and in each of these guides a slide-block 14, or 14' respectively is located which is engaged by the pin of a crank 15, or 15' respectively. The two cranks are affixed to a horizontal shaft 16 supported in bearings 16^a and 16^b and provided with a conical driving drum 17. A similar drum 18 is arranged in inverted position parallelly to the drum 17 on a suitably located and supported driving shaft, and the power is transmitted from this latter drum to that other one by means of a belt 19 which can be shifted along the two drums in known manner so as to vary the speed in 100 certain limits.

At one end of the cross-beam 9 a guide-

member-plate 20 (Figs. 2 and 3) forming two horizontal guide-ledges 20^a and 20^b is provided, and between these ledges an adjustable eccentric 21 is arranged the hub 22 of which embraces an end of a horizontal axle 23 passing through a sleeve 24 secured in the respective frontal wall of the table 12. The hub 22 projects beyond the eccentric 21 and is provided at this projecting part with a hand-lever 25, whereas the projecting end 26 of the axle 23 is threaded and is provided with a hand-wheel 27, the hub of which is threaded internally so as to form a kind of nut.

Another such arrangement and combination of parts as described in the preceding paragraph may be provided also on one end of the other cross-beam, and the axle 23 passes then from one frontal face of the table to the other frontal face but instead of an axle like 23 two separate journals may be provided at the two frontal sides of the machine, as will be clear without entering into the details of this modification.

While the device dealt with in the last two paragraphs is intended for varying the obliquity of the table, another device intended for securing the table in its adjusted position is provided at the opposite end of the cross-beam, or of each cross-beam (9 and 9'); this device consists of a vertical guide-member 28 fixed to the respective cross-beam and of a journal 29 secured in the respective frontal face of the table and having a threaded end bearing a nut-forming hand-wheel 30.

From each cross-beam (9 and 9') a rigid vertical member or support 31, or 31' respectively extends upwards, and the two members or supports carry an oblong box 32 containing the parts effecting the pre-sorting and the uniform feeding of the respective substance or material to the table 12. The box 32 is open, save two narrow cross-plates located at its ends, and below the open top, within the box, a horizontal plate 34 provided with crosswise arranged baffle-ledges 35 and 35' is provided; these ledges are practically triangular in cross-section and so arranged as regards the oblique side of each that this side is directed towards the middle of the plate 34. Thus, in Fig. 1 the oblique side of the ledges 35 is on the left and the oblique side of the ledges 35' is on the right. The object of these ledges is to facilitate the transport of the grains from the middle part of the plate 34 to the two ends thereof.

Above this plate movable oblique plates 36 and 36' are provided which are turned or swung upwards automatically, or are lifted automatically, by the rocking motion of the main-plate 8 with all parts it carries. The plates 36 and 36' form two sets, and the plates of the set 36 rise when those of the set 36' remain stationary, and reversely, in

consequence whereof the grains cannot move otherwise than in the direction to the ends of the box.

There are passages 38 38' between the frontal end-faces of the plate 34 and the opposite frontal walls 37 37' of the box 32, and below these passages intermediate bottoms 39 39' commence which are a little inclined towards each other (Fig. 1); between the upper plate 34 and the lower or intermediate plate or bottom 39 39' two sets of longitudinal walls 40 41 42 and 40' 41' 42' are arranged which are of different lengths (Fig. 4) and form parallel channels 43 44 45 and 43' 44' 45', at the ends of which the grains get into chambers 47 48 49 50 and 47' 48' 49' 50' formed by vertical cross-walls 51 52 53 54 and 51' 52' 53' 54', which are stepped differently at their upper edges. From the chambers 47—50 and 47'—50' the grains get onto the table 12 through outlet branches 55 discharging each into a separate channel 12^b of the said table. Where the channels 43—45 and 43'—45' commence, there the walls 40—42 and 40'—42' are provided with horizontally movable flaps 56 and 56' (Fig. 4) secured to short vertical axles 57 and 57' provided with handles 58 and 58', as well as with nuts 59 and 59' which can be turned on correspondingly threaded parts of said axles and by which the flaps can be secured in the position to which they have been adjusted for shutting said channels partly or wholly, as desired or required.

The manner of operation of the machine 100 is as follows:

The substance or material to be sorted is fed onto the plate 34 where it commences to travel in the two directions from the middle of the plate to the ends thereof by reason, firstly, of the rocking motion of the box as caused by the mechanical means described, secondly, of the provision of the triangular ledges 35 35', and thirdly of the flaps 36 36'. While thus travelling, a pre-sorting takes place in this way that the light grains and the foreign impurities collect upon the heavy grains. The flaps distribute the light grains and the foreign impurities completely uniformly over the entire breadth of the box. As the flaps of the two sets are opened and closed alternately, they let pass in intervals a certain amount of the grains etc., i. e., the heavy grains, as well as the light ones etc. in a height equal over the entire breadth. The pre-sorted grains fall through the passages 38 38' onto the intermediate bottom 39 39' which is subdivided into channels and chambers as above described. As each channel has the same 125 breadth and as the grain falling down from the plate 34 onto the bottom 39 39' has an equal height over the entire breadth of the said plate by the action of the flaps 36 36', each channel receives equal amounts of 130

grains and in consequence thereof also all chambers receive equal amounts of grains, equal with respect to quantity, as well as to weight, and these equal amounts then get separated from each other through the branches 55 into the channels 12^b on the table 12.

If only a part of the feed box be used, one or more of the flaps 56 56' is, or are closed. 10 It has already been stated that the table 12 can be adjusted to several degrees of obliquity, the obliquity lying at right angles to the rocking motion of the suspended system. Any change or variation in the degree 15 of obliquity can be effected in a simple manner, as well as quickly and accurately, by means of the eccentric 21 (or eccentrics, if there are two, one on one cross-beam, the other on the other cross-beam, as described) 20 which can be actuated by the hand-lever 25 in such a manner that the axle or journal 23 is lifted or lowered together with the table. But prior thereto the hand-wheel 27 must be loosened by screwing it off the hub 22 on 25 the threaded pivot 26, which is true also of the hand-wheel 30 of the fixing device located at the other end of the crossbeam, as also described. This having been done, the hand-lever 25 is turned appropriately so 30 as to turn the eccentric in one or the other direction, according as the obliquity of the table is to be increased or decreased, and then the nut-forming hubs of the hand-wheel 1 are again drawn home so as to secure the parts in their new position. 35

The means for rocking the table 12 have already been fully described and their manner of operation will be clear to every expert without further details.

40 Owing to the rocking system being suspended by means of the pendulums 2, the grains thrown against the baffle-members 35 35' are subjected to a transporting component not only in the direction to the ends 45 of the plate 34, but also in upward direction whereby the sorting process is influenced in a favourable manner.

Further advantages afforded by suspending the table by the pendulums consist there- 50 in that the machine operates free from shocks so that the foundation is not subject- 55 ed to a corresponding strain and the build- 60 ings in which such machines are housed are not caused to vibrate or shake. Besides, the 65 rocked masses can be slight, and fly-wheels may be either completely dispensed with or small ones will do. The consumption of power is comparatively slight. Adjusting or varying the number of revolutions can be 70 effected simply by shifting the belt lateral- 75 ly. Manipulating the hand-wheels can be effected while the machine is in operation.

Finally, owing to the feed-device being devised in the particular manner shown and 80 described, the output, especially seed-grain,

is remarkably uniform, the corns or grains being of perfectly like quality.

I claim:

1. In a sorting machine with sorting table and baffle members thereon, a distributing 70 device comprising in combination a box, a horizontal plate in said box, passages between the frontal ends of said plate and the opposite walls of said box, cross walls arranged below said plate and forming chambers in the box, outlet branches below said chambers discharging onto the sorting table, and means adapted to reciprocate said box.

2. In a sorting machine with sorting table and baffle members thereon, a distributing 75 device comprising in combination a box, a horizontal plate in said box, baffle ledges crosswise arranged on said plate, passages between the frontal ends of said plate and the opposite walls of said box, cross walls arranged below said plate and forming chambers in the box, outlet branches below said chambers discharging onto the sorting 80 table, and means adapted to reciprocate said box.

3. In a sorting machine with sorting table and baffle members thereon, a distributing 95 device comprising in combination a box, a horizontal plate in said box, crosswise arranged flaps arranged above said plate and being directed towards the frontal ends thereof, passages between the frontal ends of said plate and the opposite walls of said box, cross walls arranged below said plate and forming chambers in the box, outlet branches below said chambers discharging onto the sorting table, and means adapted to reciprocate said box.

4. In a sorting machine with sorting table and baffle members thereon, a distributing 105 device comprising in combination a box, a horizontal plate in said box, passages between the frontal ends of said plate and the opposite walls of said box, intermediate bottoms below said plate, longitudinal walls between said plate and said bottoms, cross walls arranged below the intermediate bottoms and forming chambers in the box, outlet branches below said chambers discharging 110 onto the sorting table, and means adapted to reciprocate said box.

5. In a sorting machine with sorting table and baffle members thereon, a distributing 120 device comprising in combination a box, a horizontal plate in said box, passages between the frontal ends of said plate and the opposite walls of said box, intermediate bottoms below said plate, longitudinal walls between said plate and said bottoms, flaps arranged at the commencement of the longitudinal walls and being adapted to close any one of the channels formed by them, cross walls arranged below the intermediate bottoms and forming chambers in the box, outlet branches below said chambers discharg- 125

ing onto the sorting table, and means adapted to reciprocate said box.

6. In a sorting machine with sorting table and baffle members thereon, a distributing device comprising in combination a box, a horizontal plate in said box, passages between the frontal ends of said plate and the opposite walls of said box, cross walls arranged below said plate and forming chambers in the box, outlet branches below said

chambers discharging onto the sorting table, a support carrying the box, vertically slotted members provided at said support, cranks, the pins of which engage the slots of said members, and means adapted to rotate said 15 cranks.

In testimony whereof I have signed my name to this specification.

GOTTFRIED NEUHAUS.
